UNITED STATES PATENT OFFICE.

GEORGE T. BRUUN, OF PITTSBURGH, PENNSYLVANIA.

ELECTRIC SYSTEM.

Original application filed January 17, 1922, Serial No. 529,916. Divided and this application filed February 9, 1923. Serial No. 618,012.

To all whom it may concern:

Be it known that I, GEORGE T. BRUUN, a citizen of the United States, and resident of Pittsburgh, in the county of Allegheny and State of Pennsylvania, have invented a new and useful Improvement in Electric Systems; and I do hereby declare the following to be a full, clear, and exact description thereof.

10 My invention relates to electric distribution and power systems which include safety switches or disconnecting switches.

The object of my invention is to protect safety switches and disconnecting switches 15 from the damage which frequently results when the switch is opened while heavy current is on the line and which also frequently causes injury or loss of life to the person who opens the switch.

20 More specifically, my object is to protect heavy-duty switches, herein called for convenience "main switches", by preventing the main switch from being opened or closed while heavy current is flowing through it.

25 My invention consists, in general, in the addition to a system including a main switch, whether a safety switch or a disconnecting switch, of an auxiliary contact device mechanically attached to the main

30 switch, or to a movable element associated with the main switch, and arranged to open, close or shunt a control circuit which includes some means, such as a motor starter, a circuit breaker, or other circuit-interrupting device, which will interrupt or reduce the current in the main circuit before the main switch is opened, thereby eliminating the possibility of dangerous arcs at the main switch. The auxiliary switch similarly protects 35 the main switch when the switch is being closed, by preventing the flow of heavy current in the main circuit until the main switch is completely closed.

In industrial motor circuits it is now customary 40 to connect a safety type switch in the motor circuit ahead of the starter, and disconnecting switches are generally used for higher voltages and higher current to disconnect apparatus from the line. It often happens that switches of this sort are opened by mistake when carrying heavy current, with resulting damage and casualties. In such cases when, for example, a motor is stopped by the safety switch instead of by the starter, a condition results

which may partly or wholly destroy the switch with consequent injury or loss of life to the operator, especially when a switch of large capacity is thus opened. The opening of such switches under load is prohibited by electrical code authorities, but it often happens that such switches are opened under load, either by mistake or in emergencies.

As applied to the control of motor circuits, my invention aims to avoid the dangers mentioned above by equipping the safety switch with an auxiliary switch through which passes the controlling current of the starter. The safety switch and the auxiliary switch are so connected mechanically that the auxiliary switch is opened before the main switch, so that the starter will open and disconnect the motor from the line before the main switch opens, and will also make it impossible to start the motor before the safety switch is positively closed and is making full contact, thereby preventing the switch from being unduly heated.

The same principle may be employed in various other connections. Thus the main switch on a starter panel may be provided with an auxiliary switch or with auxiliary contacts so connected as to keep the main line open until the main switch is fully closed, and to open the main contactor or circuit breaker before the switch is opened.

Also, disconnecting switches, safety switches or other heavy-duty switches may be provided with auxiliary contacts so connected as to operate a circuit breaker before the disconnecting or safety switch is fully open. By this means, damage is prevented in case anyone should attempt to open the disconnecting switch under load, which frequently happens, and which is likely to injure the person operating the switch and to interrupt the continuity of service through damage to the surrounding apparatus, or by setting up surges in the line.

For a further understanding of my invention, reference may now be had to the accompanying drawing, in which Fig. 1 is a side elevational view of one of the many forms in which my device may be constructed; Fig. 2 is a side elevational view of another form of my device; Fig. 3 is a fragmentary sectional view taken on the line 3—3, Fig. 2; Fig. 4 is a diagram of a typical motor circuit showing the application

of my invention thereto; and Fig. 5 is a diagram showing another typical motor circuit equipped with my invention.

Referring first to Fig. 4 of the drawing, 5 the system therein shown comprises a three-phase motor 2 provided with an automatic starter 3 and with a safety switch 4 through which the motor is connected to line conductors 5. The starter is controlled by means 10 of a stop-and-start push-button switch indicated diagrammatically at 6. The control circuit which is operated by the push-button switch 6 includes a conductor 7 in which is inserted an auxiliary contact device 8 15 which is connected mechanically to a movable part of the safety switch 4 in any suitable manner, examples of such connections being shown in Figs. 1 to 3 of the drawing.

Fig. 5 is a typical diagram of a motor circuit 20 including a hand compensator. The motor 2, as in Fig. 3, is provided with a safety switch 4, and with an auxiliary contact device 8 mechanically connected to the switch 4 and arranged to operate the control circuit which includes the conductors 9 25 and 10 and a low voltage release 11. The other connections shown in Fig. 5 are of ordinary standard construction and are therefore not described in detail.

30 The mechanical design and operating connections for the auxiliary contact device may be made in many different ways, the only requirement being that the auxiliary contact device shall open the control circuit before the main switch opens the main circuit, and that the auxiliary contact device shall close the control circuit after the main switch has closed the main circuit. By way of showing examples of such connections without, however, limiting my invention to the constructions here shown, I have illustrated on the drawing two simple methods of connecting the auxiliary contact device to the main switch.

45 In Fig. 1 the main switch consists of one or more blades 12 pivoted at 13 to the usual post 14 and arranged to fit between contact fingers 15. The main circuit conductors are shown at 16. An auxiliary blade 17 is carried by a block 18 of insulating material secured to the blade 12 or to any other movable portion of the switch. The auxiliary blade 17 engages stationary contact fingers 19 when the switch is fully closed, and the contact fingers 19 are connected to control circuit conductors 20.

The blade 12 is shown in full line on Fig. 1 in the position in which both the main switch and the auxiliary switch are fully closed. This figure also shows in dotted lines the position of the blades in which the main switch blade 12 is still in contact with the fingers 15, while the auxiliary blade 17 has broken contact with the auxiliary fingers 19. It will be evident that when the

switch of Fig. 1 is opened the auxiliary control circuit is broken before the main circuit is broken, and that when the switch is closed the main circuit is closed before the control circuit is closed.

70 Figs. 2 and 3 show one method in which my invention may be carried out by the use of an auxiliary switch of the push-button type. In these figures the blade 12 of the main switch carries a forked member 21 midway between its ends. The member 21 is arranged directly above the push button 22 of an ordinary push-button switch of the open type, the contact member 23 of which is adapted to close the control circuit 24. A spring 25 tends to hold the switch in its 75 open position. When the blade 12 is lowered to close the main circuit the member 21 forces down the push button and closes the control circuit 24 and does so after the main switch blade 12 has engaged the fingers 15 to close the main circuit.

80 The main switch may be of any usual or desired type and may be a single pole, double pole or triple pole switch, or with any number of poles. It can be of the quick make-and-break type, air-break type, oil-switch type, compensator-switch type, or any other type with solid or brush contact. This switch may be a single throw or double 85 throw switch, it may be fused or unfused, and may be arranged in all respects according to standard practice without any changes or additions except the addition of the auxiliary contact device.

90 The auxiliary control circuit contact device may be mounted on, or attached to, the main switch blade by means of insulating material, as shown in Fig. 1, or may be operated directly by the switch handle or by 95 any moving part of the switch, or even by the hook-stick for disconnecting switches, and can be mounted ahead or behind the switch blade or between the blades of the switch. The stationary contacts of the auxiliary device may be mounted on the switch base, or at a distance, or for enclosed switches may be placed on the box. Like the main switch it may be of any ordinary or desired type. If desired, the auxiliary contact device may be connected to operate a signal lamp or bell, so as to indicate visibly or audibly the condition of the main circuit.

100 My invention makes it unnecessary, as a rule, to construct safety switches with special arrangements for quick make-and-break action, as is now customary, since the safety switch breaks no heavy current when connected according to my invention. The cost of such special quick-acting switches is thus 105 saved.

110 As stated above, the auxiliary contact device may be mechanically connected not only to the main switch itself, but to any moving part associated with the switch. When my 115

- invention is applied to a safety switch enclosed in the usual box, one of the auxiliary contact devices may be connected to the cover of the box, thereby preventing the box 5 from being opened before the circuit through the switch is interrupted. This makes it possible to enclose the safety switch in an ordinary box, without the necessity of complicated mechanical interlocking mechanism 10 which is now used for preventing the cover of the box from being opened while the safety switch is closed.

The auxiliary contact device can also be arranged readily so that a substantial time 15 interval may occur between the opening of the auxiliary contact and the opening of the main switch.

It will also be noted that the present system provides for interrupting the main circuit by means of a circuit breaker or magnetic switch, without requiring any extra apparatus of this kind. The auxiliary contact device, when connected to the circuit breaker or magnetic switch ordinarily found 20 in electric circuits of any considerable capacity, will cause such circuit interrupter to act before the main switch is opened, and will maintain the circuit interrupter open until the main switch is closed. The use of 25 expensive individual circuit breakers for each motor or other appliance is thereby avoided, while providing equivalent protection.

It will thus be seen that my invention may 30 be carried out in an almost unlimited num-

ber of ways, and I therefore desire that my invention may be understood as not being limited to the particular constructions and arrangements herein described.

This application is a division of my co-pending application for Letters Patent filed January 17, 1922, Serial No. 529,916.

I claim as my invention:

1. An electric system comprising a main circuit and a translating device, a manually- and an electrically-operable switch between the circuit and the device, a holding coil requiring energization to hold the electrically-operable switch closed, and an auxiliary switch associated with the manually-operable switch for closing the holding coil circuit after the manually-operable switch is closed and for opening the holding coil circuit before the manually-operable switch is opened. 55

2. An electric system comprising a main circuit for energizing a translating device, a manually-operable switch for said main circuit, an electrically-operable switch for connecting the translating device to the main circuit, and an auxiliary circuit controlled by the manually-operable switch and adapted when energized to permit the operation and closure of the electrically-operable switch, and when de-energized, to preclude the electrically-operable switch from latching in closed position. 60 65

In testimony whereof I the said GEORGE T. BRUUN, have hereunto set my hand.

GEORGE T. BRUUN.
